TAIL PIPE ORNAMENT

Sheldon F. Feinberg, 322 Monte Vista Ave.,
Oakland, Calif.

Filed Apr. 24, 1961, Ser. No. 64,883

Term of patent 14 years

(Cl. D14—6)

FIG. 1.

FIG. 2.

The broken line showing of a portion of a tail pipe is for illustrative purposes only.

I claim:

The ornamental design for a tail pipe ornament, as shown and described.
